(57) **CLAIM**

The ornamental design for an animal feeder as shown and described.

DESCRIPTION

FIG. 1 is a front, left, top perspective view of an animal feeder of my new design;

FIG. 2 is a front, left, bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

In the drawings, the broken lines depict portions of the animal feeder that form no part of the claimed design.

1 Claim, 8 Drawing Sheets

FIG. 1

*FIG. 2**FIG. 3**FIG. 4**FIG. 5**FIG. 6**FIG. 7*

FIG. 8
